Quebec, Canada

Filed Feb. 13, 1959, Ser. No. 793,063

3 Claims. (Cl. 206—7)

The present invention relates to containers for packaging garments such as suits, coats, dresses, and the like, and more particularly to a garment packaging box made of corrugated fibreboard and adapted to contain one garment and which can be used either as a shipping container or a take home container.

An object of the present invention is the provision of a box of the character described which is adapted to maintain the suit or dress against shifting within the box during handling of the latter.

Yet another important object of the present invention is the provision of a box which maintains a dress or suit in shift free position and yet eliminates entirely the use of a hanger.

Yet another important object of the present invention is the provision of a box of the character described which can be made as a one piece non-expensive collapsible carton.

Still another important object of the present invention is the provision of a box of the character described in which the lapels of a suit coat will not become marred or wrinkled as no part of the box will contact the same.

The foregoing and other important objects of the present invention will become more apparent during the following disclosure and by referring to the drawings in which:

Figure 1 is a perspective view of a first embodiment of the box shown in partly opened position;

Figure 2 is a partial longitudinal section of the box of Figure 1, the suit coat not being shown;

Figure 3 is a partial perspective view of a second embodiment; and

Figure 4 is a transverse cross-section of the box of Figure 3, the cover member not being shown.

Referring now more particularly to the drawings in which like reference characters indicate like elements throughout, the box illustrated in the first embodiment shown in Figures 1 and 2 is made of corrugated fibreboard and comprises a body member 1, a cover member 2 and a garment clamping panel 3 which is integral with body member 1 but which could be made separate if so desired. The body member 1 has a generally rectangular shape and consists of a bottom panel 4, side walls 5 and end walls 6 and 7. Walls 5, 6 and 7 extend substantially perpendicularly to the plane of bottom panel 4. Cover member 2 is preferably integral with the body member 1 being united thereto by score line 8 extending along the top edge of end wall 6; the cover member 2 has side flanges 9 and end flange 10 adapted to overlie the side walls 5 and end wall 7 of body member 1 when the cover member is in closed position with the underface of its main panel 11 contacting the edges of side walls 5 and end wall 7. The garment clamping panel 3 consists of a main part 12 preferably of substantially rectangular shape, of upstanding lateral parts 13 and transverse part 14. The part 14 has tabs 14' folded and stapled to parts 13 so that the parts 13 and 14

2

form a non-collapsible upstanding marginal portion for the main part 12. The upper edge of transverse part 14 is integrally united to the upper edge of end wall 7 of the body member 1 by means of score line 15. The 5 clamping panel 3 is pivotable about said score line to fit within the body member 1 and engage a suit coat A over a sufficient area to also press on the sleeves of the coat. The coat A is draped on an insert 16 which consists of generally rectangular panel fitting within the body member 1 and having at its end adjacent clamping panel 3, a transverse score line 17 defining a marginal portion 18 adapted to extend at right angles against the end wall 7 and to be clamped between said end wall 7 and transverse part 14 of clamping panel 3 when the latter is in clamping position. If desired, the insert 16 can be made without marginal portion 18, the insert being held in place by the pressure of the clamping panel alone.

In practice, the coat A is draped over insert 16 and the coat and insert are then placed in body member 1 with the marginal part 18 of insert 16 in contact with the end wall 7. The clamping panel 3 is then pivoted downwardly against the suit and insert and the cover member 2 is finally closed and sealed in closed position. As lateral parts 13 have a width corresponding to the width 20 of side walls 5 of body member 1, due allowance being made for the thickness of the coat A and insert 16, it will be understood that said lateral parts 13 have their edges engaged between the main panel 4 of body member 1 and cover member 2 such that the panel 3 presses down on the suit. The inert is also positively prevented from movement because its marginal part 18 is squeezed between end wall 7 and transverse part 14 of panel 3. The clamping panel 3 which engages the sleeves also prevents movements of the latter but said panel does not contact the lapels of the suit so as to not mar or wrinkle the latter.

Obviously, the box can be made half as long as that illustrated in which case the suit will be folded over in half together with the insert.

For certain types of application it is possible to do away entirely with the insert 16. In this case it is preferable to have two flaps which will preferably be united to the body member 1 along a score line extending at the top edge of the side walls 5 of said body member 1, such that the clamping panels will engage the suit or other garment over a sufficient area so as to prevent shifting of the same despite the absence of the insert.

Such a construction is illustrated in Figures 3 and 4. 50 In this embodiment, the body member 20, cover member 21 and clamping panels 22 form a one piece construction; body member 20 and cover member 21 have the same construction as in the first embodiment but there are two clamping panels which depend from side walls 23 being pivotable relative to the same as shown in Figure 4. The second embodiment also illustrates that it is possible to provide convex clamping members instead of concave clamping members as in Figure 1.

More particularly, the convex clamping panel 22 comprises a main part 24 which is directly united to the upper edge of side walls 23 by score line 25. Lateral parts 26 and transverse parts 27 extend along the three sides of main part 24 and are interconnected by tabs 28 so as to form a non-collapsible marginal portion depending downwardly from main part 24 and adapted to engage the suit coat A at the free edges thereof. Lateral parts 26 and transverse parts 27 have a width corresponding to the width of side walls 23 of the main body 20 such that said parts 26 and 27 will be engaged between the cover member and the suit when the box is closed so as to positively contact said suit and prevent shifting of the same. Preferably the width and length of the clamping

panels 22 will be such as to engage the garment over as large an area as possible, but without contacting the lapels of the coat. In the second embodiment, the convex side panels 22 could obviously be replaced by concave panels similar to clamping panel 3 of the first embodiment; inversely, in the first embodiment panel 3 could be replaced by a panel similar to panel 22.

The cover member 2 or 21 could be made as a separate piece from the body member although it is more convenient to make said cover member as an integral part of the box.

The garment clamping panel 3 or 22 could be united to the sides of the cover member instead of the body member if so desired.

While preferred embodiments of the present invention have been illustrated and described, it is understood that various modifications may be resorted to without departing from the spirit and scope of the appended claims.

What I claim is:

1. A box for a garment, said box made of corrugated fibreboard and comprising, a body member, a cover member and a garment clamping panel integral with said body member, said body member including a bottom panel and walls integrally formed therewith, said clamping panel comprising a substantially rectangular main part and side parts which form a right angular marginal portion for said main part, said clamping panel being integrally united to said body member along a score line formed at the junction of one of said side parts of said clamping panel with a wall of said body member, such

20 25 30

that said clamping panel will fit concavely within said body member, and the main part of said clamping panel will directly contact a garment in the box, said marginal portion of said clamping panel engageable with said cover member in the closed position of the latter to cause said main part of said clamping panel to clamp said garment against shifting within the box.

2. A box as claimed in claim 1, wherein said clamping panel further includes tabs depending from said side parts overlapping and secured to adjacent side parts whereby said side parts and tabs form a noncollapsible right angular marginal portion for said main part, said clamping panel further having a size which is a fraction of the size of said body member so as to engage a portion only of said garment.

3. A box as claimed in claim 2, further including an insert on which said garment is to be draped, said insert having an end marginal portion engaged between the mutually united side part of said clamping panel and wall of said body member.
